(57) **CLAIM**

The ornamental design for metal tubing, as shown and described.

DESCRIPTION

FIG. 1 is a perspective view of the metal tubing, which may be sized and configured for use with playground equipment; FIG. 2 is a front view of the metal tubing, with the rear view being a mirror image thereof;

FIG. 3 is a top view of the metal tubing;

FIG. 4 is a bottom view of the metal tubing; and,

FIG. 5 is an end view of the metal tubing.

The broken lines shown in the figures are for illustrative purposes only and illustrate that the metal tubing may have any desired length.
